UNITED STATES PATENT OFFICE

GEORGES MOMBUR, OF VERSAILLES, FRANCE

TRANSFER DEVICE FOR REGISTERING APPARATUS

Application filed March 28, 1927. Serial No. 178,947, and in France March 29, 1926.

My invention relates to a transfer device for registering apparatus which may comprise a series of numbered disks disposed in axial alignment and so arranged that they severally present along a reference line a series of numbers, the disks running from right to left indicating the numbers of units, tens, hundreds, etc., in the usual manner.

The object of my invention is to provide a transfer device for registering apparatus which is more compact and permits a closer spacing of index numbers of a given size than the usual devices of this nature.

The invention further aims to provide a transfer mechanism which, while insuring a positive and accurate advance of the several register disks and an equally positive locking of such disks when they are not required to be in motion, is simple and rugged in construction. The accurate movements imparted to the registering disks by the transfer mechanism according to the present invention insure the alignment of the several index numbers so that the result of the integration of the register can be easily read and without possibility of confusion.

The apparatus according to the present invention is characterized by a novel connecting system between successive registering disks, said system comprising a star wheel of special design, a portion of which lies between the adjacent disks. This wheel is so formed as to perform a triple function in cooperation with a driving pin which is carried by the driving disk, driven pins which are carried by the driven disk and a mutilated locking ring which is preferably formed integrally with the driving disk. It will be understood that the term "driving and driven" may be appropriately applied when considering any pair of adjacent disks, although the driving disk of such pair will, in fact, be the driven disk with respect to a wheel disposed to the right of the latter. A particular advantage of this construction is that the separation between adjacent disks need be no greater than the thickness of the special star wheel or intermediate wheel, as it may be termed, disposed between adjacent disks, and inasmuch as no appreciable force is required

to advance the counting or register disks, this intermediate wheel may be made quite thin. The disposition of the several parts of the transfer mechanism is such that the driving and driven engagements and also the locking engagement of the parts cooperating with the intermediate wheel, all occur in the plane of such wheel, and this permits of an extremely compact arrangement of the entire registering mechanism.

Further objects and advantages of my invention will be apparent in the following detailed description wherein reference is had to the accompanying drawings, in which

Figure 1 is a front elevation of a register device employing the transfer mechanism according to the present invention.

Fig. 2 is an elevation of a disk seen in the direction of the arrow A, Fig. 1 (driving side) in its inactive and locked position.

Fig. 3 is a view of the opposite side of the same disk seen in the direction of the arrow B (Fig. 1) (driven side) in one of its working positions.

Fig. 4 is a diametrical vertical section in the direction of the arrow C, Fig. 2, or as viewed from the rear in Fig. 1.

As will be seen in Fig. 1, the register may comprise for example, five counting disks, the first disk 1 of which carries a circular row of driving ratchet teeth 2 or the like. The first disk may be made integral with the axle 3 and drive it directly. The opposite face of the first disk, that is its driving face, is identical with the driving face of any one of the other disks and is similar to the face shown in Fig. 2. It will be seen in this figure that the driving face of each disk is provided with a mutilated locking ring or flange 5 having an opening 6 of predetermined width. A catch or driving pin 7 projecting from a shoulder 7^a concentric to the rim 5 being provided opposite said opening.

In its circular course the catch or driving pin 7 may engage in one of the radial notches 8¹ formed in the teeth 8 of an intermediate star wheel 9 of special form mounted between two adjacent disks. If the notches were omitted the wheel 9 would present normally the shape of a pinion having four

teeth for instance, as shown by the dash and dot line 4 (Fig. 2), and suitably designed to cooperate with pins 10 of the adjacent driven disk, said pins having preferably a cylindrical shape. This adjacent disk is provided on its driven face with ten of such pins, as will be seen in Fig. 3, where it is desired to give indications based on the decimal system. It will be understood that with the exception of the right hand disk 1, the remaining counting disks are freely rotatable about the shaft 3. The intermediate star wheels 9 are freely rotatable about the stationary shaft 11 and function independently of one another. Each disk drives the adjacent disks of next higher order through one of the intermediate wheels 9 lying between adjacent disks. It will be apparent that the first or units disk (to the right in Fig. 1) may be driven in any suitable manner.

The form and relative disposition of the several parts hereinbefore described is such that when a driven disk is at rest in an indicating position a driven pin 10 will be engaged in a tooth gap 9¹ of the intermediate wheel 9, and said wheel will be locked against rotation because the sides of the two adjacent teeth between which such gap exists bear upon the surface of the locking ring 5 of the driving disk. It will be apparent when the parts are in the position shown in Fig. 2, that owing to the penetration of the circumferences of the said locking ring 5 and of the star wheel 9, the rotation of the latter is prevented, and since the toothed gap 9¹ of the said wheel closely engages the pin 10 of the driven disk (Fig. 3) at such time, the rotation of such disk will be prevented and its correct angular setting positively determined.

The wheel 9 will be operated once at each revolution of the driving disk by means of the catch or driving pin 7, the engagement of the latter in notch 8¹ of the intermediate wheel corresponding in angular movement to the coming of the cutaway part or opening 6 in locking ring 5 opposite a tooth 8 of the said wheel, thus allowing the rotation of the wheel to take place under the action of said driving pin.

The shape and dimensions of the intermediate star wheel 9 are determined in such a manner that, by reason of the action of the driving pin 7 of a driving disk, said wheel will be turned through an angle of 90 degrees at each actuation, this movement of the wheel causing the driven disk to be advanced one-tenth of a revolution so as to bring the succeeding numeral to the index line, the parts being then locked against displacement, as above set forth.

In this particular embodiment of my invention, the four quadrants of the intermediate star wheel are identical in form so that the operation above set forth will occur

four times during each complete revolution of such wheel.

It will be apparent that the star wheel 9 with respect to the pins 10 driven thereby constitutes a pinion, the said pins acting as the teeth of a gear meshing with the teeth 4 (Fig. 2) of such pinion (wheel 9), and driving pin 7 of the adjacent disk also acts as the tooth of a driving gear in advancing the said star wheel. Considered as gears and pinions, the driving ratio between the driving disk and intermediate wheel 9 is higher than the ratio between said wheel and the disk driven thereby because the radius of driving pin 7 is greater than the radius of driving pins 10 with respect to the axis of the disks. This results in a somewhat geared-up drive which has the advantage of bringing about a more rapid shift of the driven disk from one indicating position to another than if it were acted upon directly by the driving disk. This is desirable because it reduces the period during which it is difficult to read the index due to the movement of one or more of the disks.

It will be apparent that the use of an intermediate wheel which is actuated and in turn communicates its action in one and the same plane, allows of reducing to the utmost degree the thickness of said wheel and the necessary resulting separation between two disks. Consequently the numbers of the indicating apparatus according to the present invention will be very close together and because of the accuracy of the disk locking means hereinbefore set forth, perfectly in line, so that the registered number may be very easily read.

It will be understood that I do not limit my invention to the particular mode of execution hereinbefore specifically described and shown in the annexed drawing inasmuch as many modifications may be made in the construction without departing from the spirit of my invention, such for example as modifications concerning the number of teeth of the intermediate wheel 9 or such changes as would be required to adapt the device to a different numerical system.

Having now described my invention I declare that what I claim and desire to secure by Letters Patent of the United States is:—

1. A transfer device for registering apparatus, said device comprising a driving disk, a driven disk, a wheel between said disks, rotatable upon an axis separated from the axis of said disks, a pin on said driving disk adapted to intermittently rotate said wheel, and pins on said driven disk successively engaging said wheel and through which pins the movement of said wheel is transmitted to said driven disk, the said pins on the driving and driven disks being disposed so as to rotate in a common plane and in concentric orbits one within the other.

2. A transfer device for registering apparatus, said device comprising an intermediate wheel entering between driving and driven register disks, notches on said wheel, a catch 5 on the driving disk cooperating with one of said notches to cause said wheel to rotate through a predetermined angle during each revolution of the driving disk, ten pins arranged circumferentially upon the driven 10 disk, and flared notches upon the intermediate wheel between the first-mentioned notches and occupying a common plane therewith transverse to the axis of the wheel, one of the pins of the driven disk being engaged when 15 at rest in one of the flared notches, and means on the driving disk to lock the intermediate wheel during the time that the driven disk is not in motion.

3. A transfer device for registering apparatus, said device comprising driving and 20 driven disks, an intermediate wheel rotating freely upon an axis parallel to the axis of said disks, notches on said wheel, a catch on the driving disk engaging at each revolution in 25 one of said notches in order to cause the wheel to rotate through a predetermined fraction of turn, ten pins arranged circumferentially upon the driven disk, flared notches on the intermediate wheel between the first-mentioned 30 notches, one of the pins of the driven disk being engaged when at rest in one of the flared notches, the pins being related to said flared notches in such manner that the driven disk rotates 1/10th of a turn when the intermediate wheel effects its said fractional revolution, an annular locking surface on the driving disk adapted to be engaged by the sides of the said flared notch, and a gap in the said locking surface disposed so as to allow the 40 rotation of the intermediate wheel when said catch engages in one of the said first-mentioned notches.

4. A transfer device for registering apparatus, said device comprising driving and 45 driven disks, an intermediate wheel between said disks, a catch on the driving disk, notches formed in said wheel adapted to be periodically engaged by said catch, pins on the driven disk, flared notches formed in said 50 intermediate wheel between the first-mentioned notches, the circular path of the catch of the driving disk having a greater radius than that of the pins on the driven disk, an annular locking surface carried concentrically with the driving disk and adapted to lock the intermediate wheel by its engagement with the sides of the said flared notches, and a gap in said locking surface to allow said intermediate wheel to be rotated through a fraction 55 of a turn once at each revolution of the driving disk.

5. A transfer device for registering apparatus, said device comprising driving and driven disks in coaxial alignment, an intermediate wheel entering between said disks,

a driving pin on said driving disk, a plurality of driven pins on said driven disk, and two series of notches formed circumferentially of said wheel, and occupying a common plane transverse to the axis of said wheel, the notches of one series alternating with those of the other series, the notches of said two series being adapted to cooperate respectively with the driving pin and the driven pins whereby motion is transmitted from the driving disk 70 to the driven disk through the engagement of said pins with the intermediate wheel.

6. The device according to claim 5, further characterized in that the said driving disk carries a concentric mutilated locking ring 80 adapted to be engaged by the sides of the notches which successively cooperate with the driving pin, said engagement occurring when one of the driven pins has been securely engaged between the sides of one of the said 85 notches with which said driven pins cooperate.

7. The transfer device according to claim 5, further characterized in that a mutilated locking annulus is carried concentrically on 90 said driving disk, the said annulus and the said driving and driven pins being adapted to engage said intermediate wheel in a single plane transverse to the axis of said wheel.

In witness whereof, I have hereunto signed 95 my name.

GEORGES MOMBUR.
